(57) **CLAIM**

The ornamental design for a solar cell array, as shown and described.

DESCRIPTION

FIG. 1 is a top perspective view of a solar cell array showing our new design;

FIG. 2 is a top plan view of FIG. 1;

FIG. 3 is a bottom plan view thereof;

FIG. 4 is a rear side elevation view thereof;

FIG. 5 is a front side elevation view thereof;

FIG. 6 is a left side elevation view thereof; and,

FIG. 7 is a right side elevation view thereof.

The broken lines shown represent the portions of the solar cell array that form no part of the claimed design.
